UNITED STATES PATENT OFFICE.

ROGER W. DISBRO, OF CLEVELAND HEIGHTS, OHIO, ASSIGNOR TO THE W. S. TYLER CO., OF CLEVELAND, OHIO, A CORPORATION OF OHIO.

METALLIC DOOR.

Application filed April 25, 1921. Serial No. 464,437.

To all whom it may concern:

Be it known that I, ROGER W. DISBRO, a citizen of the United States, and a resident of Cleveland Heights, county of Cuyahoga and State of Ohio, have invented a new and useful Improvement in Metallic Doors, of which the following is a specification, the principle of the invention being herein explained and the best mode in which I have 10 contemplated applying that principle, so as to distinguish it from other inventions.

This invention relates to improvements in the construction of metallic doors, referring more especially to that class of doors used 15 in elevator enclosures, and the general object thereof is to provide a novel door which shall be light in weight, rigid and durable, and shall be simple and comparatively inexpensive to manufacture.

20 An object of my invention is to provide a door made from metallic tubular stock, in which the several parts, such as the sides and the top and base panels, are secured together by "butt-welding." By this construction, I 25 provide a very rigid, light weight door having smooth outer surfaces, and thus avoid the use of screws and nuts or similar fastening means which deface the appearance of the door and interfere with the movement of 30 the same when used in a bank of sliding doors, as in elevator enclosures.

With the above and other objects in view, I have devised the novel door which I will now describe, referring to the accompanying 35 drawing forming a part of this specification and using reference characters to indicate the several parts. To the accomplishment of the foregoing and related ends, the said invention, then, consists of the 40 means hereinafter fully described and particularly pointed out in the claims.

The annexed drawing and the following description set forth in detail certain mechanism embodying the invention, such 45 closed means constituting, however, but one of various mechanical forms in which the principle of the invention may be used.

In said annexed drawing:

Fig. 1 is a front elevation of the frame of 50 my novel door, per se,

Fig. 2 a horizontal section of the line 2—2 in Fig. 1 looking in the direction of the arrows;

Fig. 3 a vertical section through the upper

panel of the frame, being taken on the line 55 3—3 in Fig. 1 looking in the direction of the arrows, and

Fig. 4 is a vertical section through the lower panel taken on the line 4—4 in Fig. 1.

In Fig. 1 there is shown a door frame 10 60 comprising vertical side members 11 and 12 which are connected at their upper ends by a horizontal cross piece or panel 13, and at their lower ends by a base panel 14. The members 11 and 12 are constructed from 65 lengths of metallic tubular stock, being shown in the present instance as rectangular tubing having straight sides.

The cross panel 13 is made from a length of similarly constructed metallic tubing, 70 preferably of the same thickness as the side members so as to provide flush joints between the several parts when assembled, as will be described. As indicated at 15, the ends of the part 13 are placed in abutment 75 against the adjacent sides of the members 11 and 12, thus spacing the side edge members apart and providing a central opening 16 in the frame, in which may be inserted a glass pane or ornamental panel, not shown. To 80 avoid the usage of screws and nuts or the like, which are visible and project beyond the surface of the door, I secure the side members to the ends of the cross panel 13 by the process of butt-welding.

85 The base panel 14 is similarly secured between the lower ends of the side members by butt-welding its extremities to the adjacent sides of said members, as at 17. The panel 14 may be made of a wider piece of metallic 90 tubular stock than the side members or the panel 13, having portions 18 at its upper and lower edges, which compare in thickness with the side members, and having its central portion 19 of relatively less thickness. 95 It has been found that this construction of the lower panel presented a very rigid and durable structure.

100 It is to be understood that the specific shape, or cross section, of the tubular members comprising the side edges, the upper and lower panels is immaterial, and that the invention contemplates the construction of a door from metallic tubing of various shapes and designs which are secured together by 105 butt-welding to form the framework.

Other modes of applying the principle of my invention may be employed instead of the

one explained, change being made as regards the mechanism herein disclosed, provided the means stated by any of the following claims or the equivalent of such stated means be employed.

I therefore particularly point out and distinctly claim as my invention:—

1. A metallic door comprising parallel side members and transverse end members constructed of metallic tubular stock, the ends of said transverse members being abutted against the adjacent faces of said

side members and integrally united therewith.

2. A metallic door comprising parallel 15 tubular metallic members forming the sides of the door and parallel transverse tubular metallic members having their open ends abutted against the adjacent faces of said first members and integrally united there- 20 with.

Signed by me this 7th day of April, 1921.

ROGER W. DISBRO.
